DEWAXING SYSTEM

Robert E. Wilson, Chicago, Ill., assignor to Standard Oil Company, Chicago, Ill., a corporation of Indiana

Application August 31, 1931, Serial No. 560,346

8 Claims. (Cl. 196—18)

This invention relates to a dewaxing system and it pertains more particularly to a system for using liquefied light hydrocarbons such as propane and butane as a diluent and refrigerant for removing wax from viscous lubricating oils to lower their pour points.

The object of this invention is to provide an improved dewaxing system which will be more efficient than those heretofore used, which will avoid the necessity of unduly high pressures and which will increase the rate of dewaxing and decrease the cost thereof. A further object is to provide an improved refrigerating system which is particularly adapted to the dewaxing of viscous petroleum oils. Other objects will be apparent from the following detailed description.

It has been found that liquefied light hydrocarbons, such as propane, butane and, perhaps, pentane, are remarkably effective as diluents in the dewaxing process because they result in improved wax crystal formation and because of their low specific gravity and viscosity. It is usually necessary to dissolve the wax in the liquefied hydrocarbon diluent prior to the chilling step, and this solution sometimes requires temperatures as high as 125 to 150° F. At these temperatures the vapor pressure of the lighter components of the diluent mixture will be about 300 or 400 pounds which requires costly apparatus and which is objectionably hazardous. In practicing my invention I avoid the use of these high pressures by maintaining my refrigeration cycle separate and distinct from my diluent cycle, so that the light vapors which are evaporated to effect the refrigeration are not subjected to high temperatures. At the same time these light hydrocarbons are present in the refrigerating chamber in liquid form so that they have a pronounced effect on the proper crystallization of the wax, and permit the refrigeration cycle to be carried to quite low temperatures without using substantial vacuum.

In the accompanying drawing I have illustrated the layout of my improved system by means of a flow sheet on which the apparatus is diagrammatically shown.

In my system I utilize what I will call a butane cycle and a propane cycle. It should be understood that the expression "butane" as used herein and in the following claims refers to hydrocarbons or hydrocarbon mixtures having approximately the vapor pressure of butane, and that this mixture might contain pentane, isobutane, small amounts of propane, etc.; generally it may be described as a liquefied light hydrocarbon having a vapor pressure of about 30 to 40 pounds per square

inch at 70° F. Likewise, the expression "propane" refers to the lighter components, and although it preferably consists chiefly of propane, it may also contain quantities of ethane, isobutane, butane, etc.; generally speaking it may be defined as a liquefied light hydrocarbon having a vapor pressure of about 100 to 120 at 70° F. In my system there is an equilibrium between the lighter components which are removed by the flash chamber, and the heavier components which act as a diluent and which are removed from the oil by distillation; the vapors removed from the refrigerating chamber are hereinafter called propane and those removed from the oil by distillation are called butane.

The oil to be dewaxed may be a heavy petroleum distillate or a steam refined residue, it being understood, of course, that different amounts of diluent will be required for oils of various compositions, viscosities, etc. In my preferred example I will describe the dewaxing of a heavy lubricating oil which is commonly known as motor base stock. This oil may be produced from Mid-Continent crude petroleum and it preferably has a flash point of about 470° F. and viscosity at 210° F. of about 70-75 seconds Saybolt. It may be a residual treated steam refined oil or it may be a treated overhead lubricating stock, the invention being particularly applicable to the latter case because overhead lubricants of this type cannot be readily dewaxed by other methods.

In practicing my invention about 7 parts by volume of butane from storage tank 10 are conducted through pipe 11, valve 12, pump 13 and pipe 14 to mixer 15 wherein it is mixed with about three parts of wax-bearing oil (motor base stock) which is introduced through pipe 16 and valve 17. The temperature of the incoming oil may be high enough to effect complete solution of the wax in the butane in mixer 15, or separate heating means may be used to raise the temperature in the mixer to about 140 to 145° F. The butane solution is then introduced by pipe 18 into exchanger 19, where it is cooled by water from pipes 20 to normal temperatures (about 70° F.) after which it is conducted through pipe 21 and reducing valve 22 to refrigerator or chill chamber 23.

The propane is introduced into the solution from storage tank 24 by means of pipe 25 and valve 26 or by means of pipe 27 and valve 28, preferably the latter. It should be noted that the propane is added to the solution after the solution has been cooled so that the propane will not exert an undue pressure on the system. The

amount of propane introduced is sufficient to cause the refrigeration of the diluent mixture to about -20° F.

The propane vapors are removed from chill chamber 23 by pipe 29, compressed by pump 30 and conducted by pipe 31 to cooling coils 32 preferably immersed in a water-cooled bath 33. The propane pressure may be about 120 to 150 pounds in coils 33, and at about 70° it is condensed and 10 returned by pipe 34 to storage tank 24.

The chilled oil mixture and wax crystals form a slurry which is withdrawn from base of chamber 23 by pipe 35 at about -20° F. This liquid is preferably forced through pump 36 or by fluid 15 pressure through pipe 37 to filter 38 wherein the wax is removed. The butane oil mixture then passes through pipe 39, heat exchanger 40 and pipe 41 to boiler 42 where it is heated to a temperature high enough to drive off the butane 20 vapors. These vapors are withdrawn from the boiler through pipe 43, are cooled in exchanger 40 and are then passed by pipe 44 to another exchanger 45 which is cooled by suitable fluid introduced through pipe 46. Condensed butane is 25 conveyed from exchanger 45 through pipe 47, valve 48, pipe 49 and pipe 50 back to butane storage tank 10.

Since the oil in boiler 42 was heated under pressure I introduce it through pipe 51 and reducing valve 52 and pipe 53 into flash drum 54 which is maintained at low pressure, preferably atmospheric. Suitable auxiliary heating or stripping means may be employed in this drum if necessary, but when butane is used as a diluent 35 the oil leaving through flash drum 55 is usually quite satisfactory from the standpoint of flash and pour points.

Butane from the top of flash drum 54 is circulated through pipe 56, compressed by pump 57, passed through condenser 58 (cooled by a fluid introduced through pipes 59) and finally returned by pipes 60 and 50 to butane storage tank 10.

From the above description it will be seen that I avoid heating the propane to temperatures materially above room temperature and thereby 45 avoid the high pressures which would be developed if the propane were initially mixed with the waxy oil. At the same time I obtain the advantage incident to the use of propane in the wax separation bath and I obtain a rapid cooling without the necessity of a high vacuum and I 50 avoid the use of unduly high temperatures and pressures.

While the above disclosure refers to the use of butane as a diluent, it is understood that I do not limit myself to butane or to liquefied light hydrocarbons for this purpose. Excellent results may be obtained by the use of wax antisolvents, such as a mixture of two-thirds parts benzol and 60 one-third acetone, or any of the following mixtures:

	Per cent
Acetone	33
Isopropyl ether	25
Benzol	42

	Per cent
Benzol	41
Normal butyl alcohol	59

	Per cent
Benzol	45
Toluol	20
Methyl formates	35

	Per cent
Benzol	47
Ethyl formate	53
	Per cent
Butyl acetate	100
Butyl formate	100
Isopropyl ether	100

The above mixtures are exemplary only of the various antisolvents which may be used in practicing my invention. By using the propane or equivalent light hydrocarbon refrigerants, I obtain unusually low pour points and at the same time I can obtain unusually high filter rates because the liquefied light hydrocarbon appears to have a marked influence on the crystal formation of the wax.

While I have disclosed a preferred embodiment of my invention, it is understood that I do not limit myself to the details therein set forth except as defined by the following claims, which should be construed as broadly as the prior art will permit. It should be noted, for instance, that settling or centrifuging may be used instead of filtering to separate the wax from the diluted oil. Other modifications will be apparent to those skilled in the art.

I claim:

1. The method of dewaxing a viscous petroleum oil comprising, dissolving said oil at a temperature of about 140° F. in a light hydrocarbon diluent of higher boiling range than propane, cooling said mixture to a temperature of about 70°, adding liquefied propane to said cooled mixture whereby the propane becomes an effective part of the diluent, vaporizing said propane in situ to effect refrigeration of the diluent oil mixture and the crystallization of wax therefrom, compressing, condensing, and reintroducing said propane for effecting refrigeration and diluting in the chilling step, separating said wax from said chilled mixture, recovering the diluent from said oil and returning it to be mixed with more wax-bearing oil out of contact with said propane.

2. The method of dewaxing a viscous hydrocarbon oil which comprises dissolving a wax-bearing oil with a diluent at a high, wax-dissolving temperature, cooling said mixture, introducing a liquefied normally gaseous refrigerant of lower boiling range than the diluent and of lower boiling range than butane into said cooled solution whereby it supplements the diluent effect in the wax crystallization step, vaporizing said refrigerant to effect a chilling of said mixture whereby wax is caused to crystallize therefrom, mechanically removing said crystallized wax from said diluted oil, recovering said diluent and returning it to storage for reuse, and separately recovering said refrigerant and returning it to a separate storage for reuse.

3. The method of claim 2 wherein the diluent is a light hydrocarbon.

4. The method of claim 2 wherein the diluent comprises a material which is a wax antisolvent at dewaxing temperature.

5. The method of claim 2 wherein the diluent comprises an antisolvent selected from the group consisting of acetone, butyl alcohol, alkyl formates, isopropyl ether and butyl acetate.

6. The method of claim 2 wherein the diluent comprises a mixture of a material which is a wax antisolvent at dewaxing temperature and a miscibility agent.

7. The method of separating wax from oil by

the use of normally gaseous hydrocarbon diluent-
refrigerant mixtures which comprises employing
separate diluent and refrigerant cycles with an
evaporative cooling zone common to both cycles,
5 withdrawing vapors from said cooling zone for
effecting refrigeration, compressing, cooling and
reintroducing said vapors into said cooling zone,
recovering less volatile normally gaseous hydro-
carbons which are withdrawn in the solution of
10 cold wax-oil slurry from the chilling zone after
the separation of wax from diluted oil, admixing
further amounts of wax-bearing oil with said
recovered hydrocarbons, heating said diluted mix-
ture to effect solution of the wax-bearing oil,
15 partially chilling said solution and introducing
said partially chilled solution into said chilling
zone.

8. In a dewaxing system, a heated mixing
chamber, a cooler, a chilling chamber, a refriger-
ant storage, means for introducing a suitable dil-
uent and a wax-bearing oil into said mixing
chamber, means for introducing said diluted oil
through said cooler and thence into said chilling
chamber, means for passing a refrigerant from
said storage into said chilling chamber and
through said diluted oil, means for withdrawing
vapors from said chilling chamber, means for
compressing and condensing said vapors, means
for introducing said condensed vapors into said
refrigerant storage, and means for withdrawing
chilled and diluted wax-bearing oil from said
chilling chamber. 10 15

the use of normally gaseous hydrocarbon diluent-
refrigerant mixtures which comprises employing
separate diluent and refrigerant cycles with an
evaporative cooling zone common to both cycles,
5 withdrawing vapors from said cooling zone for
effecting refrigeration, compressing, cooling and
reintroducing said vapors into said cooling zone,
recovering less volatile normally gaseous hydro-
carbons which are withdrawn in the solution of
10 cold wax-oil slurry from the chilling zone after
the separation of wax from diluted oil, admixing
further amounts of wax-bearing oil with said
recovered hydrocarbons, heating said diluted mix-
ture to effect solution of the wax-bearing oil,
15 partially chilling said solution and introducing
said partially chilled solution into said chilling
zone.

8. In a dewaxing system, a heated mixing
chamber, a cooler, a chilling chamber, a refriger-
ant storage, means for introducing a suitable dil-
uent and a wax-bearing oil into said mixing
chamber, means for introducing said diluted oil
through said cooler and thence into said chilling
chamber, means for passing a refrigerant from
said storage into said chilling chamber and
through said diluted oil, means for withdrawing
vapors from said chilling chamber, means for
compressing and condensing said vapors, means
for introducing said condensed vapors into said
refrigerant storage, and means for withdrawing
chilled and diluted wax-bearing oil from said
chilling chamber. 10 15
